CLAIM

The ornamental design for a remote control, as shown and described.

DESCRIPTION

FIG. 1 shows a perspective view showing a first embodiment of our new design of a remote control;

FIG. 2 shows a front view of the remote control of FIG. 1; FIG. 3 shows a back view of the remote control of FIG. 1; FIG. 4 shows a right view of the remote control of FIG. 1; FIG. 5 shows a left view of the remote control of FIG. 1; FIG. 6 shows a top view of the remote control of FIG. 1; and, FIG. 7 shows a bottom view of the remote control of FIG. 1.

The broken lines illustrate environmental structure and form no part of the claimed design. The back view, top view, and bottom view of the remote control of FIG. 8 are respectively identical to the back view, top view, and bottom view of the remote control of FIG. 1. The back view, top view, and bottom view of the remote control of FIG. 12 are respectively identical to the back view, top view, and bottom view of the remote control of FIG. 1. The back view, top view, and bottom view of the remote control of FIG. 16 are respectively identical to the back view, top view, and bottom view of the remote control of FIG. 1.
